UNITED STATES PATENT OFFICE.

JAMES R. RUSSELL, OF BOSTON, MASSACHUSETTS.

APPARATUS FOR FORMING HAT-NAP BATS.

SPECIFICATION forming part of Letters Patent No. 252,901, dated January 31, 1882.

Application filed July 1, 1881. (No. model.)

To all whom it may concern:

Be it known that I, JAMES R. RUSSELL, a citizen of the United States, residing at Boston, in the county of Suffolk and State of Massachusetts, have invented certain new and useful Improvements in Apparatus for Forming Hat-Nap Bats; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention is in the nature of improvements on the apparatus shown and described in my United States Patents, Nos. 227,584 and 227,585, granted May 11, 1880; and the object of the invention is to take off one nap-bat instead of and as easily as two.

20 My invention consists in covering the foraminous former of my patents referred to with plates of peculiar construction, whereby there will be left uncovered for the action of the succession a space on this former only sufficiently large for collecting mixed fur and cotton enough to form a nap-bat for one hat.

25 It will be understood that the application of my present invention to my foraminous formers referred to in no wise impairs their adaptability to form two or more hat-nap bats at once.

30 In the accompanying drawings, illustrating my invention, Figure 1 is perspective view of the former. Fig. 2 is a perspective view of a solid covering-plate used for overlaying a segment of the foraminous former. Fig. 3 is a perspective view of a partly solid and partly perforated plate to cover the remainder of the former; and Fig. 4 is a perspective view of the foraminous jigger. Fig. 5 is a diagram of a single hat-nap bat formed in accordance with my present invention.

35 Results more economical in time, labor, and stock may sometimes be had in forming hat-nap bats by my inventions, by producing a single nap bat complete for one hat at a time, and to adapt my former for this purpose I place the foraminous former *a* upon the ordinary turn-table of a hat-forming machine with-

out other alterations to such machines, except preferably to bring the chute crosswise of and on a line with my former, the chute being made of wood or metal, and its mouth about ten by thirty inches on a horizontal line with a very gradual taper from the brush to its mouth.

40 As shown in Fig. 1, the former is adapted to obtain a single bat, which is subsequently divided to form bats for two hats. Now, to get from this former a bat for a single bat, I cover a portion of its perforated or foraminous top with a plate, *b*, of imperforate material, and having its outer edge curvilinear to correspond with the perimeter of the former, and having its inner edge shaped to correspond substantially to half of the finished nap, and I provide this inner edge with a vertical flange, *C*. A similar but smaller imperforate segmental plate, *d*, having a similar flange, *e*, and also a foraminous plate, *f*, attached, and a handle, *g*, 65 is placed likewise over the foraminous plate of the former *a*, the edges of the plate *f* matching closely against the flange *C*. As shown in dotted lines, Fig. 1, the flanges *C* and *e* enclose a space of substantially the area and outline of a nap-bat for a single hat, as shown in Fig. 5.

45 The foraminous plate *f* might be dispensed with and the stock collected or nap formed directly upon the foraminous plate of the former *a*; but the plate *f* is desirable for facilitating the handling of the nap-bat when formed for subsequent treatment. The provision of the handle *g* admits of the removal of the plates *d f* from the former in a ready manner when 80 the nap is to be hardened. The flanges *C e* take the place of the perimetral flange of the former *a*, and since the plates *b d* are solid the stock will be sucked down upon the plate *f* between and be confined by the flanges *C e*.

50 The jigger or hardener that I prefer to use is shown in Fig. 4, and is composed of a handle, *h*, attached to a back plate, *i*, having openings *j* of about a quarter of an inch diameter, and in any suitable number. The face-plate 85 *k* of this jigger is foraminous, as shown through the openings *j*, and this jigger is of a size and shape to fit between the flanges *C* and *e*.

55 The depositing of the stock upon the plate *f* and its subsequent treatment to harden and 90

5 prepare it for application as a nap to the hat-body are effected and carried on in any usual manner. The nap-bat, as it is taken completed from the former, is of the shape shown in Fig. 5. It is then divided on the lines 1 2 3 4. The parts *l l* form the upper side of the hat. The parts *m m* form the under brim, and the part *n* forms the tip-pieces, these several parts being applied to the hat-body by my improved machinery, for which I have applied for Letters Patent, or by other means, or in any other manner. The nap-bat, after being taken from the former, may, if necessary, be reduced to the proper size by cropping.

15 The provision of the openings *j* in the back plate of the jigger allows the air to escape through said jigger when the jigger is used to harden the bat, and thus prevents the loosening and escape of the stock.

20 In the operation of making hat-nap bats with the Gill machines commonly used, I have found that the stock comes down more at the front and sides than at the back, and taking advantage of this fact I ship the belt of the 25 turn-table so as to allow such table to stand still. I then put my improved single-nap former in such position upon the former *a* as to catch the fur or stock evenly, the suction, of course, being unchanged.

30 In the Wells former, with my arrangement of the chute, the stock will be blown over the top and snicked on.

In napping with fine furs—such as beaver, nutria, otter, and seal—I mix preferably short 35 or cut cotton in the proportion of one-sixteenth to one-eighth of cotton for each bat. With other napping-furs—as rabbit, hare, and muskrat—I use a clear fur coat and a separate cotton coat. Usually from five-eighths to an ounce of raw 40 fur is employed for a single hat-nap. I take about one-fourth of an ounce (more or less) of fur and mix it with about an equal weight, or more, of cotton for the second coat. With some kinds of fur—as long white rabbit—it is 45 best to use the medium-grade cotton unent.

My foraminous plate *f* may be of wire-cloth or perforated sheet metal.

In operating my machine I feed the required quantity of stock of fur or fur and cotton on the endless apron of a Wells or Gill machine, 50 and it passes through the roller picker or brush onto the former *f*, upon which a sufficient quantity accumulates in a few seconds. The plate *f*, with its deposit, is then, by means of the handle *g*, removed from the frame *a* to a bench 55 or table, where the jigger is employed to harden by a few shakes the nap sufficiently for subsequent handling.

The subdivision of a large former, so as to get off but one hat-nap bat at a time, may be 60 applied in other formers than those patented by me without departing from my invention.

The plates *b*, *d*, and *f* may be all in one piece, if desired, and either in this form, or made separate, as shown in the drawings, may be used 65 upon a support other than the former *a*—as, for instance, any suitable frame work that will be effective in conjunction with the turn-table and suction apparatus.

What I claim is—

1. The combination of the flanged plates *b d* 70 with the foraminous former, substantially as described.

2. The combination of the flanged plates *b d* and foraminous plate *f*, substantially as and 75 for the purpose described.

3. The combination of the flanged plates *b d*, plate *f*, and handle *g*, substantially as described.

4. A jigger having a foraminous face-plate 80 and a back plate provided with openings, whereby the air may escape from below the face-plate, substantially as described.

In testimony whereof I affix my signature in presence of two witnesses.

JAMES R. RUSSELL.
